United States Patent Office

Des. 205,123

Patented June 28, 1966

205,123

HOLDER FOR ADVERTISING LITERATURE OR THE LIKE

Albert S. Giesecke, 400 Montgomery St.,
San Francisco, Calif.

Filed Aug. 6, 1965, Ser. No. 86,479

Term of patent 14 years

(Cl. D1—3)

FIG. 1.

FIG. 2.

FIG. 4.

FIG. 5.

FIGURE 1 is a perspective view of a holder for advertising literature or the like showing my new design.

I claim:

The ornamental design for a holder for advertising literature or the like, substantially as shown.
